UNITED STATES PATENT OFFICE.

CHARLES H. STONEBRIDGE, OF NEW YORK, N. Y.

TENT.

988,401.

Specification of Letters Patent. Patented Apr. 4, 1911.

Application filed December 23, 1909. Serial No. 534,582.

To all whom it may concern:

Be it known that I, CHARLES H. STONEBRIDGE, a citizen of the United States, and residing at New York, in the county of New York and State of New York, have invented certain new and useful Improvements in Tents, of which the following is a specification, such as will enable those skilled in the art to which it appertains to make and use 10 the same.

This invention relates to tents, the body and roof portion of which are composed of textile or fibrous material, and the object thereof is to prevent injury to such tent or 15 the body or roof portion thereof, by the ripping, slitting or tearing of such body and roof portion occasioned by the expansion and contraction thereof under the influence or effects of heat and cold, or the wetting 20 and drying thereof.

It is a well known fact that a tent or the body and roof portion thereof when composed of textile or fibrous material will contract when wet and expand when dry, and 25 when said body and roof portion of the tent are composed of water proof material there is an expansion and contraction thereof under the influence of heat and cold, and this 30 expansion and contraction results in injury to said parts by the ripping, slitting or tearing thereof, but with my invention this result is avoided by means of a particular center pole construction and by means of a 35 particular eave construction whereby the expansion and contraction of the body and roof portion of the tent are provided for and 40 injury thereto consequently obviated; and with these and other objects in view the invention consists in a tent constructed as hereininafter described and claimed.

The invention is fully disclosed in the following specification, of which the accompanying drawing forms a part, in which the 45 separate parts of my improvement are designated by suitable reference characters in each of the views, and in which;—

Figure 1 is a side view of a tent made according to my invention with part thereof broken away, and parts shown in section; 50 Fig. 2 a plan view of the tent; Fig. 3 a front view thereof; Fig. 4 a horizontal section through the eave portion of the tent and taken on the line 4—4 of Fig. 1.

In the practice of my invention I provide 55 a tent body a composed of canvas or other suitable textile or fibrous material and com-

prising a bottom portion a^2 , and a roof portion a^3 , the connection between said bottom portion and said roof portion forming the eaves a^4 , and said tent is provided with a 60 front vestibule a^5 comprising side members a^6 , and a top member a^7 , and within which are flaps a^8 which form the door proper of the tent, and which may be opened when desired to permit of ingress to and egress 65 from the tent and said flaps a^8 may be folded back or entirely opened when necessary or desirable for ventilation or other purposes, and the side members a^9 of the vestibule may also be folded back at the bottom when de- 70 sired or necessary for a similar purpose. I also employ a ring or band m as shown in Fig. 1 for connecting the top or roof portion of the tent with the top of the center pole, and this ring or band may be secured to the 75 apex of the roof as shown in said figure or in any desired manner, and the top of the pole will fit therein; or the top of the roof portion of the tent may be connected with the top of said pole in any desired manner. 80 I also employ a tubular center pole b comprising three main parts, a bottom part b^2 , a middle part b^3 and a top part b^4 , and the top part b^4 is provided with a telescopic supplemental member b^5 which is tensionally 85 supported by a spring b^6 , and the parts b^2 , b^3 and b^4 are adapted to be telescoped one within another for the purpose hereinafter specified. The bottom part b^2 of the center 90 pole is provided at its lower end with a cap b^7 , and said part of the pole is provided at its upper end with a reduced extension b^9 , this construction being indicated in Fig. 1.

The lower end portion of the top part b^4 of the pole is provided at a predetermined distance from said end with a collar b^{11} below which said part is provided with an extension b^{12} , which is adapted to be inserted into the upper end of the middle part b^3 of the pole, and the supplemental member b^5 , which is telescoped into the upper end of the top part b^4 of the pole is, as hereinbefore stated, supported by a spring b^6 , and in the opposite side portions thereof are slots b^{13} , 100 and passed through the top portion of the top part b^4 of the pole is a pin b^{14} which passes through the slots b^{13} , and which limits the movement in both directions of the supplemental part b^5 and retains said supplemental part in the top part b^4 of the pole. 105

The roof portion a^3 of the canvas body of the tent is connected with the bottom por-

tion a^2 at d to form the eaves a^4 of the tent, and this connection is made, in practice, in the usual manner, by folded seams so as to give strength to these parts of the tent or 5 said connections or seams may be reinforced in any desired manner. The roof portion a^3 of the body portion of the tent is also composed of separate triangular shaped parts d^2 , which are all of the same size except 10 the part at the front of the tent, which is made wider in cross section and raised to form a part of the top member a^7 of the vestibule a^5 , and said part of the roof is also provided with an extension a^8 , which forms 15 the roof of the top of the vestibule a^5 ; and the parts d^2 of the roof are connected by seams d^3 formed by folding the edges of said parts so as to give strength to said seams, or by reinforcing said seams in any desired 20 manner.

The bottom part a^2 of the body of the tent is also composed of separate corner parts e and side parts e^2 connected at e^3 by folded or otherwise reinforced seams. The corner 25 parts e of the bottom portion of the body of the tent are triangular in form and the wider ends thereof are at the eaves of the tent while the side parts e^2 are tapered upwardly, the top edges of said parts at the eaves of 30 the tent being of the same length as the bottom edges of the parts d^2 of the roof of the tent, and by reason of this construction the shape of the tent at the eaves is that of an octagon or eight sided figure, while the bottom 35 of the tent is square or approximately so, and this gives the greatest possible space within a tent of given dimensions, and also gives a tent constructed, as herein shown and described, the greatest possible strength 40 when in position for use, and also facilitates the folding and packing of the separate parts as shown and described. It will also be seen that one of the side members e^2 of the body portion of the tent forms the front 45 thereof and the door flaps a^8 .

The side parts e^2 of the bottom of the body portion of the tent are much larger and wider than the corner parts e and are reinforced by diagonally arranged stays, 50 cords, tapes or similar devices g , and which also serves as attachments for the usual stakes at the corners of the bottom of the tent, or as attachments for ropes, cords or similar devices, by means of which connection 55 with said stakes is made, but said stakes, cords, ropes or the like form no part of this invention and are therefore not shown and described; but any suitable means may be provided whereby the bottom edges of 60 the tent body may be raised or folded up for ventilation or other purposes, as will be understood and as is done with other tents of this class.

Extending around the body of the tent at 65 the eaves thereof and preferably inside of

said eaves, is an octagonally shaped reinforced and supporting ring or band h composed of separate similar rods h^2 , connected by tubular elbow shaped keepers h^3 , and said keepers are all preferably of the same 70 length and form and said rods are all of the same length and interchangeable, and eight of said rods and eight of said keepers are employed.

In practice one of the keepers h^3 is secured in position over one of the door flaps a^8 by means of cords or similar devices i , as shown in Fig. 4. One of the rods h^2 is then inserted into said keeper, the adjacent keeper h^3 is then mounted on said rod, by inserting 80 the said rod thereinto and this operation is repeated, passing around in the direction of the arrow x in Fig. 4, and till all the rods and keepers are connected as shown in said figure. The keepers h^3 are provided centrally each with an eye or loop j and passing through each of said eyes or loops is a short cord j^2 , one end of which is provided with a hook or similar member j^3 , and the other end of which is, in practice passed 90 through the eaves portion of the tent and formed into a knot j^4 and the cords j^2 are provided adjacent to the eyes or loops through which they are passed with knots j^5 and the connection of said cords with the 95 hooks or other devices j^3 is also made by a suitable tie or knot j^6 . With this construction when the tent is not set up for use the keepers h^3 may always be suspended at the 100 eaves portion of the tent by means of the cords j^2 , and the knots j^4 , said keepers being free to move on said cords, but said movement being limited by the knots j^5 , and in the operation of placing the rods h^2 and keepers h^3 in position, as shown in Fig. 4, 105 and as hereinbefore described, the hooks j^3 at one end of said cords h^2 are connected with the corresponding eyes or loops j of another of said keepers and this connection 110 may be made as tight as desired and may be loosened or tightened at any time by simply untying and retying the knot or knots at j^6 , it being understood that the cords j^2 are 115 always preferably suspended from the eaves portion of the tent by means of the knots j^4 and this construction, as will be understood, permits of the expansion and contraction of the body of the tent at the eaves thereof or provides means whereby said expansion or contraction may be accommodated so as to prevent the slitting, tearing or ripping of the body of the tent which frequently results from such expansion or contraction. My invention is not limited, however, to this particular means for connecting 120 the keepers h^3 with the eaves portion of the tent and this connection may be made in any desired manner and said keepers may be made detachable from the eaves portion of the tent. The rods h^2 are also preferably 125 130

passed through tubular keepers or sleeves j^7 composed of any suitable, flexible material and secured at the eaves of the tent and this helps to hold the reinforcing ring or band h or the separate parts thereof in proper position.

It will be understood that the connection being the parts h^2 and the keepers h^3 of the eaves reinforcing ring or band h , is a telescopic connection, and said parts are movable, one within another, and the cords j^2 hold said parts together and prevent the separation thereof while permitting of their free movement one upon, or within another 10 within certain limits. This construction, as will be understood, provides a reinforcing ring or band for the eaves portion of the tent, which is capable of expansion and contraction, and it will be understood that the 15 supplemental spring supporting member b^5 at the top of the center pole is also to accommodate the expansion and contraction of the roof portion of the body of the tent as well as the bottom thereof and by means 20 of this construction any expansion or contraction of the body portion of the tent may be provided for and the slitting, tearing or ripping thereof which frequently results 25 from such expansion and contraction may 30 thus be avoided.

It is a wellknown fact that the expansion and contraction of the body portion of the tent made from textile material of any kind or class, and under certain conditions will 35 result either in drawing the stakes by which the tent is secured to the ground, in breaking the cords by which the body of the tent is secured to said stakes, or in slitting, tearing or ripping the body of the tent, but 40 with my improvement these changes in the condition of the body portion of the tent are provided for by the automatic, telescopic action of the top member b^5 of the tent pole and by a corresponding automatic 45 expansion and contraction of the cords j^2 by which the parts of the eaves reinforcing ring or band h are held in connection and by untying and retying the knots j^6 or a part thereof, greater expansion and contraction 50 may be provided within said reinforcing ring or band. It will be understood that my invention in this respect is not limited to the exact form or construction of the 55 eaves reinforcing ring or band h and various changes in and modifications of this feature of my improved tent construction may be made, all that is necessary in this connection being that the said reinforcing ring or band be composed of separate parts adjustably or movably connected and also connected by cords or other devices capable of expansion and contraction under conditions specified.

Another feature of my improvement consists in the form and construction of the 60 means for supporting the vestibule a^5 on

the top or roof portion thereof in order to prevent snow from accumulating thereon and also from accumulating on the adjacent part of the roof construction of the tent. In order to accomplish this result that part 70 of the roof portion of the tent in connection with which the top or roof portion of the vestibule is formed, is made wider than the other parts of the roof portion as hereinbefore described, and to support the top or 75 roof portion of the vestibule I provide a rod k composed of two separate parts connected by a sleeve k^2 and provided with a keeper k^3 with which is connected a cord k^4 , which is connected with the top of the tent 80 pole, or with any other suitable cap member or connecting device supported at or by the top of said pole, and the inner end of the rod k is, in practice, inserted into an aperture k^5 formed in the top part of said 85 pole, and the outer end thereof is inserted into a pocket or other keeper k^6 secured centrally of the top of the roof or cover of the vestibule and at the outer edge thereof, and said rod k is also provided with stay 90 cords or similar devices k^7 , which are connected with the corresponding keepers h^3 of the eaves reinforcing ring or band h at the top of the flaps a^8 or door of the tent.

In the operation of packing the tent, or 95 the separate parts thereof for shipment or other purposes, the separate parts b^2 , b^3 , b^4 of the center pole are disconnected, the parts h^2 of the eaves reinforcing band or ring h are also disconnected from the keepers h^3 100 and the parts of the vestibule supporting rod k are also disconnected and all of said parts are inserted into the top part b^4 of the center pole, and if desired, the elbow shaped keepers h^8 may also be detached and inserted 105 into said part of the center pole. The said part b^4 of the pole is then passed into or through the center part b^3 of said pole and said center part b^3 is then passed into the lower end of the bottom part b^2 of said pole, the cap b^1 being detached for this purpose, 110 after which said cap is again connected with said part b^2 of the pole. In this operation the tensionally supported member b^5 at the upper end of the part b^4 of the pole passes 115 into the tubular extension b^9 at the upper end of the bottom part b^2 of the pole, and this forms the smallest possible package for said parts and the tent body may then be folded around the telescoped parts of the 120 pole and the entire tent may thus be folded up into the smallest possible compass and be easily transported from one point to another or packed away as may be desired. The separate parts of the pole are also so formed 125 that the outside transverse dimensions of the part b^4 of the center pole are less than the inside transverse dimensions of the part b^3 , while the outside transverse dimensions of the part b^3 are less than the inside transverse 130

dimensions of the part b^2 , and with this construction the said parts fit loosely one within another, and there is no danger of said parts becoming stuck together or connected by 5 rust or corrosion or in any other way.

With my improved construction the body of the tent including the roof and bottom portion may be made of much lighter material, and in practice the eaves reinforcing 10 ring or band or the separate parts thereof may be so adjusted or regulated that there may be no transverse or horizontal strain on the roof portion of the tent body at the eaves or on the bottom portion of said tent 15 body at the eaves, all that is necessary in order to make a strong and substantial tent being to provide suitable material and suitable reinforcing means for the separate parts of the roof and bottom part of the body portion 20 where connected, and also suitable reinforcing means for the side parts of the bottom of said bottom portion of the tent.

By employing the ring or band h at the eaves of the tent, as hereinbefore described, 25 I avoid the use of all braces or similar devices connected with the center pole in any way for supporting the body portion thereof, and when the center pole is placed under the center of the roof construction, as here-

30 in shown and described and the ring or band h is placed in position, and the bottom of the tent secured in the usual manner to stakes or other devices, the tent will be firmly supported against all possible contingencies. 35

Although I have shown and described the center pole as composed of three main parts it will be apparent that as far as the construction of the body of the tent is concerned the center pole may not necessarily 40 be composed of three parts, the object in making said pole in three or more parts being to provide means whereby said parts may be packed together in the smallest possible form, and the separate parts of the reinforcing ring or band h placed therein, if 45 desired, for convenience in packing, shipping, carrying or storing the tent.

Having fully described my invention, what I claim as new, and desire to secure by Letters Patent, is;—

1. A tent, comprising a body portion composed of fibrous material and comprising a roof part and a bottom part, said tent being provided with a center pole and at one side 55 with flaps forming a door and a vestibule inclosing said door, the top of the vestibule being formed in connection with a part of the roof and being supported by a rod detachably connected with the center pole of the tent and with the top front portion of the vestibule.

2. A tent, comprising a body portion composed of fibrous material and comprising a roof part and a bottom part, said tent being 60 provided with a center pole and at one side

with flaps forming a door and a vestibule inclosing said door, the top of the vestibule being formed in connection with a part of the roof and being supported by a rod detachably connected with the center pole of 70 the tent and with the top front portion of the vestibule, said pole being composed of telescopic parts and the top member being tensionally supported.

3. A tent comprising a body portion and a 75 center pole, said body portion being composed of fibrous material and comprising a roof part and a bottom part, said roof part and bottom part being connected to form the eaves of the tent, and said eaves of the 80 tent being provided with a reinforcing ring or band, the bottom part of the tent being provided at one side with flaps forming a doorway and a vestibule inclosing the doorway, the top of the vestibule being in connection with a portion of the roof part and being supported by a rod detachably connected with the center pole and with the top front portion of the vestibule, said rod being also connected with the top of the tent and 85 with the eaves reinforcing band at the opposite sides of the top of the doorway.

4. A tent comprising a body portion composed of flexible material and comprising a 95 roof part and a bottom part, said tent being provided with a center pole and at one side with a door and a vestibule inclosing said door, the top of the vestibule being supported by a rod detachably connected with the center pole of the tent and with the top 100 front portion of the vestibule.

5. A tent comprising a body portion composed of flexible material and comprising a roof part and a bottom part, said tent being provided with a center pole and at one side 105 with a door and a vestibule inclosing said door, the top of the vestibule being supported by a rod detachably connected with the center pole of the tent and with the top front portion of the vestibule, said rod being 110 composed of detachably connected parts.

6. A tent comprising a body portion composed of flexible material and comprising a roof part and a bottom part, said tent being provided with a center pole and at one side 115 with a door and a vestibule inclosing said door, the top of the vestibule being supported by a rod detachably connected with the center pole of the tent and with the top front portion of the vestibule, said rod being 120 composed of detachably connected parts and being supported by a cord connected with the central portion thereof and with the top of the pole.

7. A tent comprising a body portion of 125 flexible material and consisting of top and bottom parts connected to form the eaves of the tent and a center pole, the body part of the tent being provided at one side with a door and a vestibule, the top of the vestibule 130

being supported by a rod connected with the front part thereof and with the pole.

8. A tent comprising a body portion of flexible material and consisting of top and bottom parts connected to form the eaves of the tent and a center pole, the body part of the tent being provided at one side with a door and a vestibule, the top of the vestibule being supported by a rod connected with the front part thereof and with the pole, said rod being supported centrally

thereof by a cord connected therewith and with the top of the pole.

In testimony that I claim the foregoing as my invention I have signed my name in ¹⁵ presence of the subscribing witnesses this 21st day of December 1909.

CHARLES H. STONEBRIDGE.
